CHECK PERFORATOR

Sigmund J. Lichter, Santa Monica, Calif.
(2869 Selby, Los Angeles, Calif. 90064)

Filed Aug. 14, 1972, Ser. No. 280,330

Term of patent 14 years

Int. Cl. D19—02

U.S. Cl. D64—10

FIG. 1.

FIG. 4.

FIG. 2.

FIG. 3.

FIG. 1 is a front elevational view of a check perforator showing my new design;

FIG. 2 is a right edge elevational view;

FIG. 3 is a rear elevational view; and

FIG. 4 is a perspective view showing the parts thereof in partially folded relationship.

I claim:

The ornamental design for a check perforator, as shown and described.
